UNITED STATES PATENT OFFICE.

JOSEPH JAUCH, OF MERIDEN, CONNECTICUT, ASSIGNOR TO THE BRADLEY & HUBBARD MFG. CO., OF SAME PLACE.

FILLING NIPPLE AND CAP.

SPECIFICATION forming part of Letters Patent No. 544,409, dated August 13, 1895.

Application filed November 26, 1894. Serial No. 530,017. (No model.)

To all whom it may concern:

Be it known that I, JOSEPH JAUCH, of Meriden, in the county of New Haven and State of Connecticut, have invented a new Improvement in Filling Nipples and Caps; and I do hereby declare the following, when taken in connection with the accompanying drawings and the letters of reference marked thereon, to be a full, clear, and exact description of the same, and which said drawings constitute part of this specification, and represent, in—

Figure 1, a plan view of a lamp-fount provided with a nipple and filling cap constructed in accordance with my invention and showing the cap in its closed position; Fig. 2, a similar but less comprehensive view showing the cap in its open position; Fig. 3, a view in vertical section on the line *a b* of Fig. 1; Fig. 4, a similar view on the line *c d* of the same figure; Fig. 5, a detached view of the cap and nipple to show the outside of the depending arm of the latter; Fig. 6, a view in vertical section, showing one of the modified forms which my improvement may assume.

My invention relates to an improvement in filling nipples and caps for lamp-founts of the type in which the filling-cap instead of being furnished with a screw-thread taking into corresponding threads in the nipple is swung as upon a pivot, and held down in place by means of a spring, the object being to produce a simple, compact, convenient, and effective construction designed with particular reference to the locking of the cap against rotation and to suggesting to the user of the lamp how the cap is to be manipulated.

With these ends in view my invention consists in the combination, with a lamp-fount, of a nipple mounted therein, a non-cylindrical cap adapted to be inserted into the said nipple and constructed to be non-rotatable therein, a shaft secured to one side of the center of the cap at a right angle to the plane thereof and extending downward through the nipple, a spring applied to the lower end of the shaft for drawing the cap downward, and a bearing for the shaft.

My invention further consists in certain details of construction, as will be hereinafter described, and pointed out in the claims.

As herein shown I employ an oval cap con-

sisting of a body *A* and an overhanging very slightly-rounded top *A'*, and an oval nipple *B* corresponding to the form of the cap and very slightly larger in internal diameter than the external diameter of the body thereof and mounted in the top *C* of the lamp-fount. I do not, however, limit myself to the use of an oval cap and nipple, as any other non-cylindrical form might be chosen, the requirements of my invention being satisfied by the selection of a form which will prevent the cap from being rotated in the nipple. The cap is provided at one of its ends with a small vertical shaft *C'* arranged at a right angle to it and passed downward through the nipple at one end thereof. Various devices may be resorted to for affording a bearing within the fount for the lower end of the said shaft. As shown in Figs. 3, 4, and 5 of the drawings, it has bearing and vertical movement in two vertically-perforated laterally-arranged bearing lugs or flanges *D D*, located at the upper and lower ends of a vertically-arranged elongated slot *D'*, formed in a concavo-convex bearing-arm *D²* formed integral with and depending perpendicularly from the nipple *B*. A spiral spring *E*, encircling the said shaft and interposed between the upper lug *D* and a collar *D³* rigidly mounted on the shaft, exerts a constant effort to pull the same downward. The long slot *D'* affords clearance for the spring, though this is not essential, as the spring might be arranged so as not to require clearance.

It will be readily understood from the foregoing description that when the cap is in place in the nipple it is locked against rotation therein by reason of the form thereof and its own form. To open the cap for the purpose of filling the lamp it must therefore be grasped and lifted in line with the nipple until its body clears the upper edge thereof, after which it may be swung around, as upon a pivot, into its full open position. Then after the lamp-fount has been filled it is swung back until its body coincides with the nipple, when the spring will at once draw it downward thereinto and lock it in place. What I wish to call attention to is that the cap is not only locked against rotation by reason of its form, but that it at once suggests to any one

who has anything to do with the lamp that it cannot be removed by rotation, but must be lifted and swung to one side. It therefore takes the place of a printed direction or oral instruction on this point.

It is apparent that in carrying out my invention some changes from the form and construction herein shown and described may be made, and I would therefore have it understood that I do not limit myself to such form and construction, but hold myself at liberty to make such changes and alterations as fairly fall within the spirit and scope of my invention. Thus, instead of supporting the shaft of the cap in a bearing-arm formed integral with the nipple, I may employ for the purpose such a construction, for instance, as shown in Fig. 6, which shows an independently-formed bracket E, secured to the lower edge of the nipple by soldering or otherwise and having two vertically-perforated bearing-flanges E' E², through which the shaft passes. By preference this bracket is reinforced by a brace F arranged diagonally between its lower end and the lamp-fount.

I am aware, however, that, as stated at the outset of this description, non-rotatable swinging filling-caps are old, and I do not, therefore, claim such broadly.

Having fully described my invention, what I claim as new, and desire to secure by Letters Patent, is—

1. The combination with a lamp-fount, of a non-cylindrical nipple mounted therein, a non-cylindrical cap conforming in shape to the shape of the nipple and held against rotation by its shape and the shape of the nipple, a shaft secured to the cap at one side of the center thereof and at a right angle to

the plane thereof, and extending downward 40 through the nipple, a spring applied to the lower end of the shaft for drawing the same downward, and a bearing within the fount for the shaft, substantially as described.

2. The combination with a lamp-fount, of 45 an oval nipple mounted therein, an oval cap conforming in shape to the shape of the nipple, but smaller in external diameter than the internal diameter of the nipple, a shaft secured to one end of the cap, and passing 50 downward through one end of the nipple, a spring applied to the shaft for drawing it downward, and a bearing within the fount for the said shaft, substantially as described.

3. The combination with a lamp-fount, of a 55 non-cylindrical nipple mounted therein, a non-cylindrical cap conforming in shape to the shape of the nipple and held against rotation by its shape and the shape of the nipple, a shaft secured to the cap at one side 60 of the center thereof, and at a right angle to the plane thereof, and extending downward through the nipple, a spring applied to the lower end of the shaft for drawing the same downward, and a bearing for the said shaft, 65 consisting of a perpendicularly arranged arm formed integral with the nipple, and provided with lugs or flanges through which the shaft passes, and in which it is free to move vertically, substantially as described.

In testimony whereof I have signed this specification in the presence of two subscribing witnesses.

JOSEPH JAUCH.
